UNITED STATES PATENT OFFICE.

JOHN F. LINDBERG, OF CHICAGO, ILLINOIS, ASSIGNOR TO RELIANCE DIE AND STAMPING COMPANY, OF CHICAGO, ILLINOIS, A CORPORATION OF ILLINOIS.

ELECTRIC CONDENSER.

Original application filed April 17, 1922, Serial No. 552,728. Divided and this application filed January 26, 1924. Serial No. 688,676.

To all whom it may concern:

Be it known that I, JOHN F. LINDBERG, a citizen of the United States, residing at Chicago, in the county of Cook and State of Illinois, have invented a certain new and useful Improvement in Electric Condensers, of which the following is a full, clear, concise, and exact description.

My invention relates to electric condensers and to electric resistances which are well adapted for establishing restricted leakage between the sides of condensers, though the invention is not to be thus restricted. The invention also resides in combining a condenser with any suitable resistance in a manner to permit relative movement between the sides of the condenser without disturbing the adjustment of the leakage that is effected by the resistance.

The condenser of my invention includes flattened coiled sheets of dielectric material and sheet metal, the latter surrounding the former and constituting one side of the condenser, and a flat sheet of metal constituting the remaining side of the condenser and located within the bore of the coiled dielectric and movable longitudinally thereof to adjust the capacity of the condenser.

The resistance of my invention includes two terminals and an element of insulating material assembled with said terminals and capable of receiving markings of a writing instrument, there being two thin spaced apart layers of current conducting material upon said element of insulating material individual to and respectively contacting with said terminals and projecting beyond the same to be capable of receiving and merging with a marking employed as resistance to unite said terminals.

In the preferred embodiment of the invention the two thin spaced apart layers of current conducting material are formed by broad lines of india ink. These resistance terminals may be easily and suitably connected by means of lead pencil lines drawn between them of a breadth or number to secure the desired resistance adjustment. The pencil lines readily merge at their ends with the broad ink lines. Hitherto it has been endeavored to join metallic resistance terminals by means of lead pencil lines but it has been found that the ends of the lines do not contact as they should with such terminals.

I will explain my invention more fully by reference to the accompanying drawing in which Fig. 1 is a perspective view illustrating an electric condenser and a resistance device associated therewith in accordance with the preferred embodiment of the invention; Fig. 2 is a sectional view on line 2—2 of Fig. 1; Fig. 3 is a sectional view on line 3—3 of Fig. 1; Fig. 4 is a perspective view illustrating the component parts of the structure of Fig. 1 in separated relation; and Fig. 5 is a circuit diagram illustrating the relation of the resistance to the condenser.

Like parts are indicated by similar characters of reference throughout the different figures.

The condenser side 1 is in the form of a metal sheet that is shaped into a flattened coil, one end of the sheet having a flap portion 2 which completes the formation of this condenser side into an envelope. A dielectric 3, preferably a thin sheet of mica, is also formed into a flattened coil and is enclosed by the condenser side 1. The sheets 1 and 3 are desirably placed together to be coiled and flattened in one operation. The remaining condenser side 4, formed of a sheet or ribbon of metal, is surrounded by the flattened dielectric coil 3 and is movable back and forth in order that the capacity of the condenser may be adjusted. For the sake of convenience, the projecting end of the condenser side 4 is bent at right angles and curled to constitute a handle 5. The condenser side 1 and the dielectric 3 are formed with holes 6 through which mounting screws 7 may be passed to secure the condenser to any suitable form of support such as the board 8. I connect a resistance between the sides of the condenser in such a manner that the capacity of the condenser may be varied without disturbing any resistance adjustment that has been effected.

To this end the resistance is mechanically assembled with one condenser side in order that the resistance terminal which is connected with this condenser side may be normally fixed with respect thereto. The resistance terminal of the other condenser side has sliding or other changeable engagement therewith in order that the condenser capacity may be adjusted without disturbing the resistance adjustment between the condenser sides.

In the preferred embodiment of the invention the resistance element includes a body of insulating material 9, such as a sheet of paper, this insulating element being clamped between an extension of the dielectric 3 and a metal clip 10 which is in gripping engagement with the extension of the dielectric that is tucked in between the sides of the clip. The clip, as a whole, is of ⁵ U-shape and each side of it is also U-shaped in cross section. One terminal 11 of the resistance is preferably formed by a broad line of india ink whose carbon is a suitable conductor. The other terminal 12 of the resistance is a similar broad line of india ink. These spaced apart resistance terminals 11 and 12, being very thin layers of current conducting material, may readily be joined through lines of carbon 13 made by a writing instrument, preferably a pencil, lead pencil lines readily merging with the ink lines. The resistance terminal 11 is firmly held in contact with the condenser side 1, being firmly pressed into engagement with ¹⁰ this condenser side by reason of the fact that its mounting 9 is tightly received between said condenser side and the dielectric. The resistance terminal 12 is firmly held in engagement with the metallic clip 10, the mounting 9 being firmly clamped between one fold of the clip and the dielectric. The inner opposed faces of the clip and the condenser side 4 are in sliding relation so that ¹⁵ the capacity of the condenser may be varied without modifying the resistance adjustment. While the resistance element is

preferably mechanically assembled with the non-sliding side of the condenser, the invention is not to be thus limited.

The condenser of my invention is of particular service when employed in connection with wireless systems of communication and the resistance element of my invention is of particular service when employed in connection with a condenser for the purpose of ⁴⁰ effecting adjusted leakage between the condenser sides. ⁴⁵

Features not herein claimed form the subject matter of my original application Serial No. 553,728, filed April 17, 1922, of ⁵⁰ which the present application is a division.

While I have herein shown and particularly described the preferred embodiment of my invention I do not wish to be limited to the precise details of construction shown as changes may readily be made without departing from the spirit of my invention, but having thus described my invention I claim as new and desire to secure by Letters ⁵⁵ Patent the following:

An electric condenser including flattened coiled sheets of dielectric material and sheet metal, the latter surrounding the former and constituting one side of the condenser; and ⁶⁰ a flat sheet of metal constituting the remaining side of the condenser and located within the bore of the coiled dielectric and movable longitudinally thereof to adjust the capacity of the condenser.

In witness whereof, I hereunto subscribe my name this 25th day of May A. D., 1923.

JOHN F. LINDBERG.
